UNITED STATES PATENT OFFICE.

ROBERT H. F. SEWALL, OF NEW ORLEANS, LOUISIANA.

RIVER-BANK PROTECTOR.

1,200,767.

Specification of Letters Patent.

Patented Oct. 10, 1916.

Application filed December 13, 1913. Serial No. 806,650.

To all whom it may concern:

Be it known that I, ROBERT H. F. SEWALL, a citizen of the United States, residing at New Orleans, in the parish of Orleans and State of Louisiana, have invented a new and useful River-Bank Protector, of which the following is a specification.

This invention has for its object to provide means for utilizing the current power of a stream or river and to control and direct such current by a combination of spur-dams and other instrumentalities so arranged and disposed as to cause the swift current to pass along the concave bends at a safe distance therefrom or nearer middle-stream, when the power of the current will scour the bottom of the channel to deepen the same instead of washing away the foundation of the banks.

A further object is to cover or cushion the entire slope of the bank along the concave bends, with a plurality of pockets or pools of slackened water or eddies caused by a combination of spur-dams and other instrumentalities, the pockets, pools or eddies while protecting the bank from the scouring of the current, will at the same time cause a rebuilding of the bank where caving previously prevailed.

A still further object of the invention being a structure designed to cause the proper accumulation of silt or other sediment carried with the water so that the bank of the stream or river which has the greatest wear thereupon due to the projection of the stream thereagainst, will be artificially supplemented instead of disgorged, and by means of which the main current of the stream is properly diverted to the deep water.

A still further object of the present invention is the provision of a plurality of dikes or dams that are adapted to be disposed at an acute angle to the river bank, those directly in the bend being of greater length than the ones upon either side thereof so that the greatest supplementing of the bank will be at the bend, such dikes or dams being preferably disposed at an approximate angle of 45 degrees to the main outline of the bank, and projected upstream.

A still further object of the invention is the provision of a plurality of sunken re-ceptacle dams adapted to be disposed farther out in the stream and to alternate

with the bank dikes or dams, so as to co-operate therewith to assist in the desired supplementing of the bank and at the same time prevent the disgorging thereof.

60

A still further object of the present invention is the provision of means whereby the dikes or dams may be driven or preferably sunken by hydraulic means, each dike or dam being composed of a plurality of sections, each section of which is individually driven or sunken and coupled with all sections to form a dike or dam of the desired length.

65

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

70

In the drawings—Figure 1 is a diagrammatic view showing two bends of a river with the present invention applied as in use. Fig. 2 is a diagrammatic cross section through the river bed and banks with the present invention applied. Fig. 3 is a view similar to Fig. 1 with a single bend of a river and in which the cribs are used in conjunction with the shore dams or dikes.

75

Fig. 4 is a top plan view of one of the cribs used to supplement the dike adjacent the bank. Fig. 5 is a view in elevation thereof looking in the direction of the arrow Fig. 4. Fig. 6 is a top plan view showing the method of connecting the vertical members of the dikes or dams together. Fig. 7 is a view in elevation of a portion of one of the bank dikes or dams showing the position of the sectional members thereof.

80

Fig. 8 is a top plan view of one of the rectangular piles used in connection with either of the respective dams. Fig. 9 illustrates one method of providing means for supplementing a river bank, the piles being in the position they assume during the sinking thereof. Fig. 10 illustrates the natural formation of the supplemental bank due to the piles as driven in Fig. 9. Fig.

85

11 is a detail view showing the coupling between the driven and driving piles, by means of which the latter may be withdrawn after the driven pile has been properly sunk. Fig. 12 is a perspective view of the coupling

per sec. Figs. 13, 14 and 15 are detail views of concrete piles designed to be used in lieu of the other forms.

Referring to the drawings, and more particularly to Figs. 4 and 5 thereof, A designates the upper caving bank of the river and B the lower caving bank. The force exerted by the current flowing between the banks will be substantially along the lines indicated by dotted arrows α , under ordinary conditions, the tendency of the current being to cut into the off shore at the bend A and also at the off shore of the bend B. By placing the spur dams 1 at the off shore of the bend A and with their outer ends inclined upstream at an angle of approximately 45 degrees, and by alternating therewith the interposed sunken dams 2, the deep swift current entering the curved portion A of the stream will be retarded along the outer side of the stream, setting up an agitation opposite the dams which results in deepening the stream at the bend A where this retarding occurs. The retarding of the outer side portion of the curved stream at A likewise exerts a drag upon that portion of the current approaching the bend B with the result that the scouring action of the current at the bend B will be materially reduced.

The submerged dams 2 are preferably composed of round piles and coöperate with the dikes or dams 1, and more especially at high water divert the swift current, the upper ends of the dams 2 being so disposed as to assist the dikes or dams 1 in diverting the swift current at high water away from the bank protected by the dikes or dams 1 and as particularly illustrated in Fig. 2, such diversion as clearly illustrated in diagram Fig. 1, causing the swift current to follow the arrows α and thus be prevented from producing the undesirable caving-in effect as indicated by the arrows σ .

As illustrated in Fig. 3, the shore or bank dikes or dams 1', that are disposed directly at the bend are inclined upstream similar to the dikes or dams 1, while the dikes 1^a are disposed upstream and downstream relatively to the dikes 1' at the same angle with relation to the banks, but are of a lesser length than the central dikes 1'. The bracing cables 2' are connected as clearly illustrated in Fig. 1 to the dikes or dams 1' and 1^a, so that the same are properly placed and form in reality a cantaliver structure, so that all of the dikes coöperate to produce a single bracing structure throughout the bend in the river. This structure can also be applied to the dikes 1 as illustrated in Fig. 1.

Adapted to supplement and assist the dikes 1' and 1^a are the supplemental dikes or dams 3, which are constructed in the form of V-shaped cribs, with their side

wings so disposed, that the apices are downstream with the receptacle portions upstream, thus providing means to collect and receive the silt in such body, while a portion will be collected adjacent the apex thereof, due to the eddies formed in the current by such dikes or dams.

It will be noted that the cribs 3 are disposed to alternate with relation to the dikes 1' and 1^a, the numbers of both being increased or decreased according to the size of the bend of the river and the distance from the shore that it is desired to supplement.

As clearly shown in Figs. 4 and 5, each crib 3 is composed of a plurality of driven rectangular piles 4, provided with tongue and groove meeting edges 5, these sections being driven either by pile driving or sunken hydraulically, as will presently appear, the upper ends being disposed below the surface of the stream as in the dikes 2, and so as to provide means unobstructing the surface of the current, and thus increasing the life of the crib itself while in place. These cribs are braced with cross wires 3', while disposed upon the front edges thereof, is one or more strands of wire netting 6, constituting means for preventing any material disposed within the cribs or therebetween, such for instance as rubbish or branches that may be thrown therein to assist in the accumulation of the silt or mud, from being floated out into mid-stream.

The main river bank dikes 1' and 1^a, are constructed in sections, the main vertical sections 7 themselves being composed of a plurality of members adapted to be superposed one above the other, and having attached thereto, strips 8-8', the strip 8 having connected thereto, two strips 9, which form a dove-tail groove while the strip 8' is provided with the tongue 10 for interengaging the groove 9 of the strip 8. These members 7 are thus properly secured together by means of the respective strips 8 and 8', and may be driven in position by means of a pile driver, but are preferably hydraulically sunken one at a time, there being provided a channel 14 through the body of the pile 7 for the reception of a hose H.

In positioning the various piles 7 in place, the one nearest the bank is primarily positioned, being eased down to the mud or bottom of the river, water then being pumped through the hose H, the lower end of which is adjacent the lower end of the pile, and thus displacing the mud or bottom below the end of the pile to permit of the easy insertion of the same, all of which is well known. The channel 14 is of such a size, as to permit of the introduction of the hose therewithin, and also to permit of the reduction of the water due to back flowing.

- therein, during the hydraulic sinking of the pile. After the first pile 7 has been positioned, each succeeding one is then placed in position, the tongue members 9 being fitted upon the tongue 10 of the adjacent pile during the downward sliding movement of the pile and after the lower end of such succeeding pile has been positioned upon the bottom of the river, water is pumped 5 through the hose H in the channel 14, and thus the mud or silt is displaced adjacent the tongue of the driven pile and removed so as to permit of the easy introduction of the succeeding pile.
- 10 In order to maintain the proper direction and straight line during the driving or sinking of the piles, the longitudinal bracing strips 11 are placed upon either side of the pile structures as soon as the first pile is driven, and bolted to every third or fourth pile as the work progresses.

It is also apparent that the various driven elements of the main and auxiliary or supplementing dikes, may be round piling, it 25 being mainly the present idea to place the dikes 1 and 1', at the angle as illustrated in Fig. 1 relatively to the main bank, with the crib-shaped supplemental dikes or dams in the position as shown, so as to supplement 30 the main dikes 1 at the extreme bend of the river.

Thus it will be seen that any silt or mud carried downstream will be pocketed upon both sides of the respective main dikes or 35 dams, and that flowing outwardly toward the space between the dikes or dams 3, it will be accumulated with the brush or other material held in place by the netting 6, so that the river bank at such point will be 40 supplemented continually due to the precipitation and collection of the silt or mud at such point.

Round piling driven to a proper depth under certain conditions will not only catch 45 and hold in place the mud or silt that sloughs from the slope of the river bed, but will also tend to pin the base of the slope of the river bed firmly, so as to prevent any sliding or sloughing of any kind into the 50 deep water channel, thereby insuring at all times, a free and open passage for the flow of the main current.

By the arrangement as shown in Fig. 1, by means of which the swift and deeper 55 water will follow the arrows c, it is evident that a clear channel will be cut and maintained, thus dispensing with continual dredging operations to keep the channel the desired depth; and also the swift water will 60 pass a safe distance from the lower bank of the bend B, and therefore not cut away the bank as under normal or natural current flow.

As shown in Figs. 9, 10, 11 and 12, it is 65 desired to supplement the bank 15 of Fig. 9,

to a point as at 16 in Fig. 10, this being accomplished by driving or sinking the piles 17, so that they will have their upper ends at such a distance above the bank or bottom of the stream according to the fill or supplementing desired.

In order to best accomplish the driving or sinking of the piles 17, the near piles 18 are first driven, and then the strips 11^a, similar to strips 11, heretofore described, are projected outwardly in the stream as the inner piles 17 are successively driven. In order to produce the inclined contour to the upper ends of the outer piles 17, metal coupling shoes 19, H-shaped in vertical end 80 elevation, are attached to the lower ends of the driving piles 20, the lower beveled edges 21 of the shoes being so constructed that they readily fit upon or are detached from the upper ends of the piles 17 after the piles 17 have been sunken or driven to the desired position. These sunken spur-dams produced by the piles 17 are to be arranged inclinedly similar to the spur-dam 1, or may be positioned at any desired angle and distance apart to accomplish the result desired.

In Fig. 13, a concrete pile 22 having the metal core 23, which not only reinforces the pile but produces a water introduction channel for hydraulic sinking is provided.

In Figs. 14 and 15, the concrete pile 24, has a removable pipe core 25, which is made readily removable after the coalescing of the concrete, by spirally winding rope 26 100 about the pipe and incasing such coil in paper. In this manner, one terminal of the rope is projected exteriorly of the pile and is pulled upon to produce a space about the pipe 25, and thereby permit the easy withdrawal of such pipe 25 and to leave a bore through the pile for hydraulic sinking.

In all of the piles designed for hydraulic sinking the pipe or hose for furnishing the water may be inserted within the bore to a 110 point adjacent the bottom so that the exhaust may pass up the bore about the hose or pipe; or such hose or pipe may be connected in the top and the water permitted to exhaust outwardly from the lower end 115 of the pile.

The concrete piles, as shown in Figs. 13, 14 and 15, may be poured or rolled piles, and when desired are provided with the metal spiral reinforces 27.

It is also my intention where necessary and desirable to fill the bores or channels after the piles are driven or sunken with concrete, which may or may not be reinforced with metal rods.

What is claimed is:

1. An apparatus of this character, including a plurality of supplemental bank forming means for rivers and the like, disposed at an acute angle with relation to the bank,

- the pocket formed by the acute angle being disposed upstream, and a plurality of augmenting dikes disposed beyond the bank forming means and alternating therewith.
- 5 2. An apparatus for protection of river banks, including a plurality of main dikes extending from the river bank at an acute angle, the outer end of each dike being projected upstream, a plurality of supplemental crib dikes disposed to alternate with the bank dikes, and beyond the outer ends of the bank dikes, each of the latter being V-shaped in top plan with the apices thereof disposed downstream.
- 10 15 3. An apparatus for protection of river banks, including a plurality of main dikes extending from the river bank at an acute angle, the outer end of each dike being pro-

jected upstream, a plurality of supplemental crib dikes disposed to alternate with the bank dikes and beyond the outer ends of the bank dikes, each of the latter being V-shaped in top plan with the apices thereof disposed downstream, and a netting secured to the outer edge of each of the V-shaped 25 dikes to assist in holding the collected precipitate from being carried away by the main stream.

In testimony that I claim the foregoing as my own, I have hereto affixed my signature in the presence of two witnesses.

ROBERT H. F. SEWALL.
